UNITED STATES PATENT OFFICE.

ARCHIBALD F. FLETCHER, OF BROOKLYN, NEW YORK, ASSIGNOR OF TWO-THIRDS TO VALENTINE GLEASON, OF NEW YORK, N. Y., AND JOHN VICTOR CARRAHER, OF WASHINGTON, DISTRICT OF COLUMBIA.

HYDROCARBON-BURNER.

SPECIFICATION forming part of Letters Patent No. 400,905, dated April 9, 1889.

Application filed March 13, 1888. Serial No. 267,084. (No model.)

To all whom it may concern:

Be it known that I, ARCHIBALD F. FLETCHER, a citizen of the United States, residing at Brooklyn, in the county of Kings and State of New York, have invented certain new and useful Improvements in Hydrocarbon-Burners; and I do hereby declare the following to be a full, clear, and exact description of the invention, such as will enable others skilled in the art to which it appertains to make and use the same.

My invention relates to certain new and useful improvements in burners for utilizing as a heat-producing agent the heavy hydrocarbons, and particularly the residuum from petroleum after the separation therefrom of the volatile constituents (a product that can only be ignited at a very high temperature.)

It relates, further, to apparatus for utilizing said burner in steam-boiler furnaces, as will more fully appear from the following specification.

In the accompanying drawings, illustrative of my invention, Figure 1 represents my improved burner in elevation. Fig. 2 represents the same in central section. Fig. 3 represents a cross-sectional view on a plane indicated by the line 3 3 of Fig. 2. Fig. 4 represents an end view of the burner, and Fig. 5 represents the manner of employing the same in a steam-boiler furnace or the like.

Similar letters of reference indicate similar parts throughout the several views.

In the drawings, C indicates the outer wall of the burner, and consists of a conical-shaped hollow piece of metal externally screw-threaded at its outer end, as shown, and having attached thereto a nozzle, L. The said nozzle L is flattened and expanded, as shown more fully in Fig. 4, so as to present a large area for the issuance of the flame, and to form a kind of mixing-chamber for the vaporized hydrocarbon and steam or air used in the operation.

Within the shell C is arranged concentrically the inner tube or pipe, M, extending to the entrance of the nozzle L and opening into the latter. This inner tube is intended for the supply of hydrocarbon to the flame, said hydrocarbon being conducted to the said tube

by means of a branch pipe, G, leading from any suitable source of supply.

In Fig. 5 is illustrated a desirable manner of applying my improved burner to the generation of steam in a steam-boiler furnace, 55 the construction and arrangement of parts of said boiler-furnace and its adjuncts adapting it to co-operate with the burner proper for the production of very high heating effects.

The burner is located, as shown, in front of the combustion-chamber N of the furnace, and together with an inclosing-sleeve, B, penetrates the front wall of said chamber, air being supplied to the shell B from without 65 through the bell-mouthed pipe B'.

The inner pipe or tube, M, of the burner is supplied, as above described, with heavy hydrocarbon through the supply-pipe, G, and the space intermediate between the pipe M 70 and the outer wall, C, of the burner is supplied through the pipe with hot air or superheated steam under constant pressure. When hot air is employed, it is furnished through a pipe, F, provided with a suitable shut-off 75 cock, a, to a pressure-chamber, H, from which it is supplied, under a pressure of about forty-five pounds, to a coil, D, located in the combustion-chamber of the furnace in the path of the issuing burner-flame. From the 80 coil D the air passes to the burner, the back-pressure upon the coil being regulated, however, by the pressure-chamber K, which maintains it at a constant pressure of, say, forty-five pounds, which I have found in practice to give excellent results.

The hot air in its passage through the burner heats the inner tube, M, so highly as to vaporize the heavy hydrocarbon, so that it enters the nozzle in the form of a vapor and meeting at its exit 90 the current of hot air at once enters into combustion therewith, the peculiar form of the nozzle retaining the air and vaporized hydrocarbon momentarily until an intimate admixture of the two is effected, whereupon it 95 issues from the flattened end in a broad sheet of flame. The additional air drawn in through the sleeve B adds to the completion of the combustion, and just before the flame passes into the boiler-flues it encounters 100

finally an additional supply of hot air issuing from the ports J of a hollow bridge-wall at the rear end of the chamber. These ports communicate with a broad flue, A, arranged 5 immediately below the floor of the chamber and opening freely into the open air, as shown. By virtue of the last-mentioned supply of hot air the combustion of the vaporized hydrocarbon is practically completed and the products of combustion pass into the boiler-flues at an intense heat.

Instead of employing air for supplying the space between the inner tube, M, of my burner and the wall C thereof, I may with equally 15 good results employ superheated steam for that purpose. In this event I close the stop-cock a and open a stop-cock, b, located in a pipe, E, connected with the steam-boiler. The steam is supplied to the pressure-chamber H under the prescribed pressure found 20 most advantageous. It becomes superheated in the coil D and passes to the burner under the pressure allowed by the pressure-chamber K. In said burner it exercises the same 25 functions as the superheated air just described, becoming finally decomposed in the high furnace heat, its oxygen uniting with the hydrocarbons in the phenomenon of combustion, and its hydrogen swelling the mass 30 of combustible gases.

I may also operate the apparatus as follows, and I have found this use attended with great advantages: Closing the stop-cock b and opening the stop-cock a, I admit to the pressure-chamber H, through the pipe F, water at a 35 pressure of forty-five pounds. I then admit through the stop-cock c in the pipe leading from the chamber H to the coil D a small quantity of water into said coil. Closing the 40 said stop-cock, I light a fire in the combustion-chamber beneath the coil D, which then acts as a generator of steam. As soon as the gage on the pressure-chamber K shows a pressure of, say, five pounds, I admit a small quantity 45 of hydrocarbon into the inner tube, M, of the burner, thereby starting the operation. I then turn off the water-supply through the pipe F and open the stop-cock b, thereafter supplying steam from the boiler to the coil D. 50 The pressure-gage on the receptacle H will then indicate the pressure on the boiler, and the gage on the receptacle K will indicate the pressure on the coil D. It is evident that by regulating the admission of steam from the

receptacle H by means of the stop-cock c, I 55 can maintain the pressure in the receptacle K and coil D at forty-five pounds, which I have found to be a safe limit, whatever may be the pressure of steam on the boiler.

It is incident to my invention, as heretofore 60 stated, that the superheated steam or air has the effect of converting the oil residuum or its equivalent into vapor before it reaches the nozzle L, and at the point of entrance into the said nozzle commingles with the vapor thus 65 formed, creating a highly-inflammable mixture which develops an extremely high temperature on ignition. The oil residuum being in the gaseous condition on entering the combustion is in the state most favorable for combination with the oxidizing steam or air, and the high temperature of the latter adds very 70 largely to the calorific power of the mixture.

It is evident that instead of using the residuum of petroleum, other heavy hydrocarbons 75 may be employed in carrying out my invention, and among these I may mention tar, and particularly coal-oil tar, raw and dead petroleum, and the like crude products of small cost, and of which but little use can at present be made. 80

My burner is designed principally for use in the generation of steam for factories, railroads, steamers, house-heating, and the like, and is especially adapted to these uses by reason of the complete combustion attained, 85 there being practically no resultant smoke from the burning operation.

Having thus described my invention, what I claim is—

A hydrocarbon-furnace consisting of a combustion-chamber, a burner for heavy hydrocarbons entering said combustion-chamber and provided with an inner and outer passage concentric with each other, a supply-pipe for furnishing hydrocarbon to one of said passages, a supply-pipe for furnishing superheated steam or air to the other of said passages, a superheating-coil located within the combustion-chamber, and pressure-chambers intermediate between said coil and burner, 90 and said coil and its supply-pipe, substantially as described.

In testimony whereof I affix my signature in presence of two witnesses.

ARCHIBALD F. FLETCHER.
